US0D1106824S

(12) United States Design Patent (10) Patent No.: US D1,106,824 S
(45) Date of Patent: * Dec. 23, 2025

(54) CONTAINER

- (71) Applicant: NICOVENTURES TRADING LIMITED, London (GB)
- (72) Inventors: Wesley Steven Jones, Lexington, NC (US); Nicholas H. Watson, Westfield, NC (US); Pankaj C. Patel, Clemmons, NC (US); Laya Katina Palmer Horton, Winston-Salem, NC (US); Ryan A. Bailey, Raleigh, NC (US); Michael E. Laut, Raleigh, NC (US); Prasad Joshi, Raleigh, NC (US)
- (73) Assignee: Nicoventures Trading Limited, London (GB)
- () Term: 15 Years
- (21) Appl. No.: 29/850,294
- (22) Filed: Aug. 18, 2022

CLAIM

The ornamental design for a container as shown and described.

DESCRIPTION

FIG. 1 is a top perspective view of a container of the present invention showing our new design;

FIG. 2 is a bottom perspective view thereof;

FIG. 3 is a left elevation view thereof

FIG. 4 is a right elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines shown in the drawings depict portions of the container that form no part of the claimed design.

1 Claim, 6 Drawing Sheets
